United States Patent Office.

EDWARD S. CROSS, OF LIME ROCK, CONNECTICUT.

Letters Patent No. 61,001, dated January 8, 1867.

IMPROVED BED-BOTTOM AND SEAT.

The Schedule referred to in these Letters Patent and making part of the same.

TO ALL WHOM IT MAY CONCERN:

Be it known that I, EDWARD S. CROSS, of Lime Rock, in the county of Litchfield, in the State of Connecticut, have invented certain new and useful improvements in Bed-Bottoms and Seats; and I do hereby declare that the following is a full and exact description thereof.

My invention relates to springs and their connections, by which the slats which support the bed or cushion, are connected to the bedstead or equivalent support.

I will first describe what I consider the best means of carrying out my invention as applied to a bedstead. The accompanying drawings form a part of this specification.

Figure 1 is a longitudinal vertical section.

Figure 2 is a plan view.

Figure 3 is a longitudinal section through the spring and adjacent parts when loaded.

Similar letters of reference indicate like parts in all the figures.

The drawings represent the novel parts, with so much of the other parts as is necessary to show their relation thereto.

A is the bedstead, which may be made in any of the approved forms, either highly ornamented or extremely plain, as represented. *a a* are hook-formed brackets bolted upon the inside of the bedstead. B B B are parallel slats to which are secured hook-formed brackets, *b*, by means of stout rivets as represented. C and D are castings, having bolts or axes *c* and *d* passing through them as represented, and having ears or spurs C' D' arranged as represented. These castings, C and D, are connected to the hook-like brackets *a b*, so as to turn thereon in vertical planes as indicated in the drawings. E E, &c., are spiral springs of stout brass wire or other suitable material, applied upon the castings C and D, so as to take hold of the spurs C' and D' in the manner represented. When the weight of one or more persons is applied upon the slats B, or when at any subsequent period the load thereon is changed or moved, the castings C and D turn on their respective axes *c* and *d* so as to assume various inclinations in the vertical plane; while the spring E stretches and contracts according to the well-known laws of springs of this character. The whole constitutes an easy and effective support for the slats, allowing great freedom of motion and great elasticity in the support. My construction also allows of being adjusted with very great nicety to different loads and to compensate for different strengths of springs and for inequalities in the proportion of the parts. If the spring is found to be too long, it is sufficient to turn one of the castings C or D half round in the one direction or the other, so as to slide corresponding projections C' or D' along in the helical space between the several coils of the spring E. If it is turned half round in one direction, it shortens the spring and increases its tension; if it is turned half round in the opposite direction, the act lengthens the spring and diminishes the tension. The casting C or D may be turned many times around if necessary in order to effect the proper adjustment. All the parts of my invention may be made by machinery with great facility and economy, and the work may be put together with great delicacy by very ordinary workmen. It will be obvious that the same construction and arrangement may be applied to chairs, benches, sofas, and all varieties of seats, as well as to beds.

Having now fully described my invention, what I claim as new in bed-bottoms and seats, and desire to secure by Letters Patent, is as follows:

1. I claim the spiral spring E, attached to the end of the slat B, or of the bedstead A, by means of an attachment inserted into the end of the spring, and having one or more spurs standing in the helical spaces in the spring so as to allow of being turned, substantially as and for the purpose herein specified.
2. I claim, in combination with the above, the within-described arrangement of the castings C and D, and axes *c* and *d*, adapted to turn in the vertical plane, substantially as and for the purpose herein specified.

EDWARD S. CROSS.
